ATTORNEY.

UNITED STATES PATENT OFFICE.

JOSEPH C. SPARROW, OF CLEVELAND, OHIO.

WINDOW REFRIGERATOR.

Application filed February 9, 1925. Serial No. 7,792.

My invention relates to window refrigerators, by which I mean box-like receptacles to be fitted into the inner sash groove of a window-frame with the inner sash resting upon its top, or in the outside groove with said sash lowered, extending outwardly from the house, and accessible from the interior of the latter, the general type and application of which are well and generally known.

Heretofore a type of such refrigerator has been made and used, which consisted of a single unitary box-like receptacle, non-extensible laterally and whose front or inner side or wall was formed by a hinged door. When the device is used in a window frame of greater lateral dimension than the receptacle, it was necessary to fill in the blank space so formed by means of a separate sheet or strip of metal, wood, or the like, which procedure has been found oftentimes inconvenient and awkward.

The object of my invention is to provide a refrigerator of the above-described general type which will embody a cooling receptacle of fixed dimensions, having a front or inner door accessible from the interior, provided with means for varying the lateral dimension of the device whereby it may be fitted in any ordinary window frame, and at the same time completely fill the window space laterally, thereby avoiding the necessity of using the previously described extra strip.

The said invention consists of a structure hereinafter fully described and particularly pointed out in the claim.

In the annexed drawing:

Figure 1 represents a front view of a window refrigerator embodying my invention.

Fig. 2 represents a horizontal section taken upon the plane indicated by line II-II, Fig. 1.

Fig. 3 represents a transverse section taken upon the plane indicated by line III-III, Fig. 1.

Fig. 4 represents a section taken upon the plane indicated by line IV-IV, Fig. 1, and

Fig. 5 represents a perspective view of the said device.

As shown in the illustrated embodiment of my invention, my improved refrigerator comprises two elements, a sheet-metal main member 1, and an auxiliary or lateral sheet-metal member 2. Member 1 is of rectangular form, and is provided with a top wall 3, a bottom wall 4, two end walls 5 and 5', and a back wall 6, all fixed relatively to each other so as to form a cooling space of fixed dimensions. The front or inner wall is formed by a door 7 hinged at the bottom and swinging inwardly of the window frame, a suitable latch 8 being provided which detachably engages a fixed angle 9, for holding the door in its closed position. This door therefore, when closed, forms with the top, bottom and end walls of the main member, a completely enclosed cooling space of fixed dimensions.

The end wall 5 has its front edge portion provided with a vertical bead 10 which engages the window groove (not shown), as will be understood.

Telescoping with the other end portion of the main member is the previously mentioned auxiliary lateral member 2. This member 2 is substantially the same depth as member 1, but just sufficiently greater in depth so as to fit and slide upon the outside thereof, as shown in Figs. 2 and 4. The top and bottom front edge portions of member 1 are formed with the beads, 11 and 12 respectively, into which similar beads, 13 and 14 formed upon the front top and bottom edge portions respectively of member 2, fit and slide, as will be understood.

Member 2 is open in front and has the single lateral wall 15, the front edge portion of which is provided with a bead 16 adapted to fit on the other frame groove (not shown).

It will be noted from the above description, that the refrigerator is adjustable and may hence be fitted to different sized window frames, that at all times the window opening which receives the refrigerator is completely closed, so as to exclude the outside air, and that a cooling compartment is at the same time provided, which may be completely closed by the door.

What I claim is:

A window refrigerator comprising a main

member consisting of a rectangular receptacle having a top, a bottom, back and two end walls all relatively fixed with relation to each other, and a door adapted to form a complete front of such member; and a laterally positioned member slidably mounted on the exterior of said main member and adapt-

ed to vary the lateral dimensions of the refrigerator, said slidable member having a depth substantially the same as that of said main member, and having its front open.

Signed by me this 27th day of January, 1925.

JOSEPH C. SPARROW.
